UNITED STATES PATENT OFFICE.

MICHAEL C. RYAN, OF PHOENIX, NEW YORK.

STOP-MOTION.

1,004,594.

Specification of Letters Patent.

Patented Oct. 3, 1911.

Application filed February 16, 1910. Serial No. 544,281.

To all whom it may concern:

Be it known that I, MICHAEL C. RYAN, a citizen of the United States, residing at Phoenix, Oswego county, New York, have 5 invented certain new and useful Improvements in Stop-Motions; and I do hereby declare the following to be a full, clear, and exact description of the invention, such as will enable others skilled in the art to which 10 it appertains to make and use the same.

This invention relates to certain improvements in stop motions for silk doubling and winding machines and the like and the objects and nature of the invention will be 15 readily understood by those skilled in the art in the light of the following description of the accompanying drawings showing what I now consider my preferred embodiment from among other constructions and 20 arrangements within the spirit and scope of my invention.

An object of the invention is to provide certain improvements in stop motions for doubling, winding and other machines of 25 similar character and purpose, and whereby when a thread or strand breaks the winding bobbin or reel will be almost instantaneously stopped and locked or gripped against continued rotation thereby preventing continued rotation of the bobbin after it has been thrown from operative position, or relation 30 with respect to its driving means.

A further object of the invention is to provide certain improvements in arrangements and combinations whereby a simple 35 and highly efficient stop motion will be produced, readily adaptable to doubling and other silk or thread machines.

The invention consists in certain novel 40 features in constructions and arrangements of parts and in combinations and arrangements of elements as more fully and particularly set forth hereinafter.

Referring to the accompanying drawings:—Figure 1, is a detail front perspective view of a stop motion embodying my 45 invention, the parts being shown in normal operative position, a winding bobbin and the silk strands thereto being shown. Fig. 50 2, is a detail end elevation of the structure shown in Fig. 1, the parts being shown in normal operative position, the winding bobbin being shown in cross section, the cover or side wall of the case containing the trip 55 mechanism being removed. Fig. 3, is a

view similar to Fig. 2, but showing one silk strand broken and the parts in bobbin stopping position. Fig. 4, is a detail front elevation of the stop-motion-carrying arm (the bobbin being partially shown in section) with the parts in the position shown by Fig. 3. Fig. 5, is a horizontal section on the line 5—5, Fig. 2. Fig. 6, is a detail perspective of the bobbin lifting finger and its operating finger piece, and the electric 60 switch controlled thereby. Fig. 7, is a detail perspective view of details of the trip mechanism.

My stop motion is particularly designed for detecting breaks in the strands passing 70 from the supply bobbins to the winding bobbins of silk doubling machines although it is adapted for application to winding, reeling and other silk and thread handling machinery.

In the example shown, in the drawings, 2, is a winding bobbin having end trunnions 3, which can be formed by a spindle or shaft. The bobbin is also provided with a friction drum or hub 4. The bobbin is driven by a 80 constantly rotating friction disk 5, carried by drive shaft 6. The bobbin trunnions rest removably in the vertical slot bearings 7, so that the bobbin is vertically removable from the machine and rests by gravity on the friction driving disk and is rotated by the frictional engagement of the hub 4 on the edge 85 of said driving disk.

In a doubling machine a plurality of winding bobbins are employed driven by 90 separate friction driving disks on the drive shaft 6, to wind the silk strands on the bobbins and to draw the same through or over various tension devices and from the supply bobbins. Each winding bobbin draws 95 strands from two or more supply bobbins as is well understood by those skilled in the art. I have shown only one winding bobbin and one stop motion coöperating therewith, and have not illustrated the structure 100 of the doubling machine inasmuch as those skilled in the art are familiar with such machines and will readily understand the application of my invention thereto.

I show the stop motion carried by a suitable bracket at its lower end bolted or otherwise secured to a suitable longitudinal beam of the machine frame, and rising therefrom in the form of an arm 10, terminating below the winding bobbin, and comprising a 110

box or casing 11. This bracket carries one or more detectors or spring arms 12. In the present instance, I show two such arms each at its outer or free end provided with an eye 13, to receive a strand or thread 14 on its way from a supply bobbin to the winding bobbin. An independent detector 12, is provided for each strand 14, passing to the bobbin. Each detector can consist of a vertically movable spring metal wire at its outer free end having the eye 13, and at its inner end formed into a coil 15, confined and rockable on a metal supporting rod or shaft 16, and having a rear upwardly projecting stop or contact end 17, to limit the downward movement of the free end of the detector, while the upward movement of the detectors mounted on horizontal rod 16, is limited by the back turned horizontal outer end 18, of said shaft, said stop end 18, being arranged above the detector arms to be engaged thereby. The downward movement of the free ends of the independent detector arms is limited by the upward engagement of their projecting rear ends 17, with the horizontal metal rod 19, parallel with and above metal rod or shaft 16. The constant tendency of the detector arms is to assume the lowered positions with their rear ends 17, in contact with the stop rod 19. The silk strands passing up through the eyes 13, of the detectors to the winding bobbin, hold said detectors swung upwardly against the stop arm 18 with their contact ends 17, away from stop rod 19, by reason of the fact that said strands are stretched or under tension. Should either strand part or break, the tension on its detector arm will be immediately relieved and said arm will instantly drop until its contact end 17, engages the stop rod 19. This operation or action is taken advantage of through the medium of electric devices to bring about the action of the stop motion to practically stop and lock the winding bobbin almost instantaneously with the breaking of any strand passing to said bobbin.

The stop rod 19, and shaft 16, are insulated from each other in and are carried by an insulating block 20, fixed on the front portion of the stop motion supporting bracket. The electrical conducting rod 19 and shaft 16, are shown passing completely through said block and projecting laterally therefrom and at their short threaded projecting ends opposite the detectors are provided with nuts 21, independently clamping the rod and shaft to the block and forming binding posts for the electrical connection of conductors 22, 23. The shaft 16, is preferably axially movable or turnable in the block for the purpose of adjusting the stop end 18, up or down to vary the upward limit of the swing of the detectors for the purpose of increasing or diminishing the

tension on the silk strands passing through the eyes thereof. The shaft is clamped in the desired axial adjustment by tightening the nut of the binding post 21, thereof.

The conductor 22, extends from any suitable source of electrical energy and the shaft 16, and conducting-wire detectors thereon are constantly in circuit therewith and the circuit therefrom to the conducting and stop rod 19, is normally broken because of the normal separation of the detectors from the rod 19.

The conductor 23, extends from the binding post 21, (electrically connecting rod 19 and said conductor) to normally "dead" electro-magnet or motor 24, and electrically connects the same with rod 19. The magnet 24, is arranged in the box or casing, hereinbefore mentioned, and is insulated from the walls thereof and constitutes the releasing device for the trip mechanism normally holding the binding bobbin grip or lock out of action.

The binding bobbin stop and locking or gripping device comprises a pair of upwardly projecting oppositely arranged cooperating jaws 25, 26, having concaved faces which if so desired can be provided with friction gripping faces 27, formed by leather or other suitable friction or cushioning material secured thereto. These jaws are approximately alike in formation and each is formed with a depending shank or lever 28, rigid with its jaw. The two shanks are crossed and at the point of intersection are pivotally jointed together to form a fixed fulcrum point. This fulcrum is formed by a pin or stud 29, projecting laterally from the upper portion of the stop motion bracket arm, and supporting the bobbin gripping jaws. The lower ends of the two levers formed by the jaws and their shanks 28, are pivotally joined respectively, to the under ends of a pair of links 29', which at their lower ends are pivotally joined to the upper end of a vertically movable slide 30, passing vertically through said box or casing and guided thereby in its vertical reciprocation. The toggle or lazy-tong arrangement thus provided, is such that when the slide 30, moves upwardly the gripping jaws will be swung apart to non-gripping or inoperative position, but when the slide moves down said jaws will be moved toward each other to gripping position.

Means are provided, preferably constantly acting, to throw the slide downwardly to move the jaws to gripping position with sufficient force to perform their locking or stopping function. As a means which can be conveniently employed for this purpose, I show an expansive coiled spring 31, on the slide and within the box and compressed between the top wall of the box and a loose or slidable collar 32, on the

slide. Means are also provided for normally holding the slide elevated against the tension of said spring to hold the jaws in their normal inoperative positions, said means comprising a trip whereby the slide can be quickly released to permit its spring to act in forcing the same down to bring the jaws to gripping position should a thread or strand break. As an example of means which can be employed for this purpose, I show a vertically disposed elongated flat dog 33, arranged longitudinally of the slide in a longitudinal slot cut therethrough. This dog is carried by and projects beyond the slide and is mounted to rock on a transverse pin 34, arranged near the upper end thereof and by which the dog is carried and mounted in the slide. The transverse flat upper end of the dog is arranged beneath the loose collar 31, and forms the stop limiting downward movement of the collar, and the formation of said upper end of the dog is such that the pressure of the spring 31, thereon through the collar, yieldingly holds the dog in its normal upright position so that the dog can swing to move its lower end laterally only by slightly raising said collar against the tension of said spring.

The lower end of the dog is formed with a laterally projecting tooth or downwardly facing shoulder 35. The trip for engaging the tooth 35 of said dog to normally hold the slide and gripping jaws in "set" or inoperative position comprises a vertically rocking trigger, catch or lever mounted to rock on a fixed transverse shaft or pin 36, and comprising an elongated upwardly extending arm 37, having a tooth or shoulder 38, at its upper extremity and at its lower end mounted on said pin 36, and having a laterally projecting tooth or upwardly facing shoulder 39, arranged a distance above the floor of said casing or box and normally in the path of movement of the dog tooth 35. The arrangement is such that when the slide is in its normal "set" or elevated position, the tooth 35, of its dog will rest and bear down on the shoulder 39, of said lever or trip and will thereby be upheld while the gripping jaw-throwing spring tends to swing said lever or trip to remove shoulder 35, from the path of the dog and to swing the upper end of the arm 37 inwardly and laterally away from the vertical wall of the box against which the upper end of the arm normally rests. The said trip is normally held and maintained in its locking or slide-upholding position by the extended or stop end 40, of the vertically swinging horizontally arranged magnet armature 41, fulcrumed or pivotally mounted between its ends in said box on horizontal or transverse fixed pin 42. The stop end 40, of the armature, normally bears down on the top edge of the trip arm 37, with the shoulder 38 of said arm bearing inwardly against the end edge of said stop end which thus holds the trip arm in its normal position and against inward swing and upholding the trip shoulder 39 in its elevated position 70 sustaining the slide.

When the magnet is energized its armature is drawn down thereby lifting its stop end from holding engagement with the trip arm shoulder, whereupon the gripping-jaw-throwing spring will rock the trip to release the dog therefrom and permit downward movement of the slide. The downward movement of the slide is limited by the engagement of the lower end of the dog with the floor of the box or casing, thereby limiting the closing movement of the gripping jaws. The limit of the closing movement of said jaws can be varied by raising or lowering the pivot of the dog in 85 the slide.

The instant the dog is released from the trip, the trip is returned to its normal operative position by a spring 43, applied thereto and also to the armature to normally hold the same from the magnet and its stop end to the trip arm. The trip is swung by spring 43 to its normal position and the armature stop end immediately moves down on the trip arm and holds the same in operative set position. When the gripping jaws are swung open or restored to their normal "set" position, by hand, and against the tension of the jaw-throwing spring, the slide is drawn up and during this operation, the slide dog, which had been swung laterally on its downward movement, bears against the edge of the trip, and when the tooth of the dog moves up past the shoulder of the trip, the dog immediately swings to its normal upright position with its tooth resting on the trip shoulder and thereby holding the parts in "set" position with the jaws "open".

The gripping jaws are arranged below 110 and in front and rear of the friction hub of the winding bobbin and when "set" or in their normal positions are disengaged therefrom so as not to interfere with the free rotation of the bobbin. When, however, a strand passing to said bobbin breaks, the magnet is immediately energized and the jaws are released and tightly grip said hub of the bobbin and lift the bobbin to raise said hub thereof from driven contact with the friction driving disk. The action of the jaws is so rapid that the jaws on the parting of a strand almost instantly grip the bobbin and stop the rotation thereof, thereby preventing continued rotation of the broken and unbroken strands thereon, which is exceedingly objectionable in practice.

Inasmuch as the operator may desire to turn the bobbin by hand before the opera- 130

tion of tying the broken strand is completed and before the bobbin is dropped into frictional driving engagement with its driving disk, and as it is necessary to open the gripping jaws before the bobbin can be thus turned by hand, I provide means for holding the bobbin lifted from its driving disk after the gripping jaws have been opened and removed from gripping engagement with the 5 bobbin. For example, I show one of the gripping jaws provided with a lifting finger 44, arranged to one side of the jaw and beyond the end of the bobbin and projecting downwardly and inwardly in the vertical 10 plane of the end trunnion of the bobbin. This finger is mounted to swing vertically under friction on a transverse shaft in the upper end of the jaw and is provided with an upwardly projecting finger piece 45, whereby the finger can be moved to and from 15 normal and lifting or supporting positions. The finger is normally swung down from operative position with respect to the bobbin trunnion, but when a thread has broken and 20 the jaws have gripped the bobbin, the finger piece 45, is then swung laterally and the lifting finger thereby swung up into lifting engagement with the trunnion of the bobbin gripped and elevated by the jaws. The 25 jaws can then be opened to "set" position releasing the bobbin, and the lifting finger will prevent the bobbin dropping into driving engagement with the friction disk. While thus held by the finger the bobbin can 30 be freely rotated by hand. When the broken thread has been tied and the operator desires to again start the bobbin on its winding operation, the finger piece 45 is swung forward and the finger is thereby lowered 35 40 dropping the bobbin onto its driving disk.

The electric circuit for energizing the trip operating magnet is controlled by any one of the hereinbefore mentioned detector arms and is normally broken because of the separation of the detector arms 17 (forming one contact of the circuit closer or switch) from the conducting stop rod 19 (forming the other end stationary contact of the switch or circuit closer). When a thread or strand 45 50 breaks, its detector and tension arm drops and closes the magnet energizing circuit by engagement of the arm 17 with the rod 19, and thereupon the winding bobbin of such strand is lifted and locked by the gripping jaws. The detector of the broken thread remains in its dropped circuit closing position until its strand has been tied and the bobbin has again started to wind and has thus 55 60 restored the tension to the strand necessary to lift the detector and break the circuit.

Such being the state of facts, in the specific example illustrated, it is obvious that if the jaws are opened to hold the bobbin up by the lifting finger, as hereinbefore described, the magnet would again immedi-

ately release the trip and cause closing of the jaws, unless some means are provided for breaking the circuit at some other point when a detector is in circuit closing position. 70

I hence provide a second and normally closed switch in circuit with the magnet and adapted to be opened by the closing of the gripping jaws. To this end I provide a knife switch comprising a depending knife 75 contact 47, carried by one of the jaws and in circuit therewith and usually through the same to the stop motion supporting bracket which can be electrically connected with the return to the source of electrical energy. I show this knife contact carried by the finger piece 45, to swing therewith and with the bobbin lifting finger. The stationary member or contact 48 of the knife switch is fixed to the upper end of the arm of the stop motion supporting bracket and is suitably insulated therefrom but is electrically connected with the magnet coil by connection 49, so as to be in circuit with said coil. The arrangement of the switch contacts is such that when the jaws are in their normal "set" position and the lifting finger is in its normal depressed position, said contacts will be in engagement and the switch closed to complete the circuit from the magnet coils 90 to the metal supporting frame of the stop motion. When the jaws move to bobbin-gripping-and-lifting position, the knife switch is opened inasmuch as the jaw carrying the knife member of the switch moves 95 the same from contact with the fixed member of the switch, and the circuit is thereby broken and the magnet deenergized even though the detector be in circuit-closing position. The knife switch still remains open 100 and the circuit broken when the jaws are again thrown back to "set" position inasmuch as the movement of the lifting finger to bobbin-lifting position throws the knife member of the switch forward from position 105 where it will engage the fixed switch member when the jaws are opened. The magnet will thus remain deenergized until the bobbin is ready to start its winding operation and has been restored to winding position by the lowering of the lifting finger, which action throws the knife member of the switch into circuit closing engagement with the fixed member thereof, but before this switch is thus closed, the circuit has been 110 broken by the lifting of the detector arm or arms. 115

As at present advised, I do not wish to limit all features of my invention to any particular trip mechanism and releasing means therefor nor to the electrical devices controlled by the breaking of a thread, inasmuch as other means might be employed for controlling my gripping jaws, and furthermore I do not wish to limit certain other 120 125 130

features of my invention to the particular bobbin stopping means described, and it is evident that various changes and modifications might be resorted to in the forms, constructions, and arrangements of the parts described and that elements might be omitted or other elements added, without departing from the spirit and scope of my invention, and hence I do not wish to limit myself to the exact disclosure hereof.

What I claim is:—

1. In a stop motion, a rockable shaft, means whereby the same can be secured in the desired adjustment, a swingable detector arm having a thread eye at its free end, said arm being mounted to swing on said shaft, means to limit the movement of the arm in one direction, and a stop portion carried by said shaft to limit the swing of the arm in 20 the opposite direction, the position of said stop portion with respect to the arm being adjustable by rocking the shaft.

2. In a stop motion, a rockable shaft, means for securing the same in a desired axial adjustment, a swingable detector arm mounted to rock on said shaft and having a thread eye, said shaft having a back-turned end above said arm forming a stop to limit the upward movement of the arms, a stop 30 rod, said arm having a rear projected end to engage said stop rod to limit the downward movement of the arm.

3. In a stop motion, a support, a block of insulating material thereon, a conducting contact rod projecting from and carried by 35 said block and provided with means for connecting an electric conductor thereto, a rotatably adjustable conducting shaft mounted in said block and projecting therefrom parallel with said rod and having means for coupling an electric conductor therewith, and a detector arm of conducting material mounted to swing on said shaft, and having a thread eye and a rearwardly projecting stop end 45 normally out of contact with said rod and adapted to move into contact with the rod to limit the downward movement of the arm, said shaft provided with a stop arm adjustable therewith to limit the swing of said 50 detector arm.

4. In a stop motion, a vertically movable tension and detector arm having a thread eye and an electric-contact and stop end, a support on which said arm is fulcrumed, an 55 adjustable arm-engaging stop carried by and moving with said support and limiting upward movement of said arm and determining the tension thereof on the thread, and a stationary electric-contact stop adapted to be 60 electrically engaged by said end when the detector drops from normal position.

5. In a stop motion, a spring conducting- 65 material tension and detector arm at its vertically movable free end having a thread eye, a conducting shaft on which said arm is

mounted to swing, a stationary contact, said arm formed with a coil rockable on said shaft and terminating in a free contact end normally out of contact with said stationary contact and adapted to engage the same when 70 the arm drops to normal position, and a stop limiting upward swing of the thread eye end of said arm and formed by a bent-back end of said shaft.

6. In a stop motion, in combination, stop 75 mechanism, electric controlling means therefor comprising an electric motor, a support, and a normal open switch controlling said motor and comprising an axially-adjustable conducting shaft provided with and carrying 80 a detector-arm stop, swingable detector arms of conducting material formed with intermediate bearing eyes rockable on said shaft and having thread eyes and movable contact portions extending radially therefrom, and a conducting rod parallel with 85 said shaft and forming the stationary switch contact and adapted to be engaged by the contacting portion of any detector arm when the same drops from normal position. 90

7. A stop motion, comprising a support bracket, circuit closing detector arms carried thereby, a pair of coöperating bobbin gripping devices mounted thereon, operating and controlling means for said devices carried by said bracket and comprising an electric motor in circuit with said detector arms. 95

8. A stop motion comprising coöperating bobbin lifting and clamping levers, in combination with actuating means, and controlling devices comprising a thread receiving detector arm, and an electric motor in circuit therewith. 100

9. A stop motion comprising winding-bobbin grasping and elevating jaws, in combination with means for actuating the same on their operative movements, means normally holding said jaws in set position, and a trip device. 105

10. A stop motion comprising coöperating bobbin clamping and lifting jaws, actuating means therefor, and controlling devices for said actuating means. 110

11. A stop motion comprising a pair of pivoted opposing coöperating clamping jaws, means for holding said jaws set in inoperative position, controlling devices for said means, and jaw actuating mechanisms. 115

12. A stop motion comprising a pair of coöperating clamping jaws provided with means for simultaneously moving the same in opposite directions, a trip mechanism for holding said jaws set, and devices for actuating said trip. 120

13. A stop motion comprising a pair of coöperating pivoted bobbin clamping jaws, in combination with a spring and connections for simultaneously moving said jaws to clamping position, means for holding said jaws in opened or set position, and mecha- 125 130

nism controlled by the breaking of a thread for operating said means to release said jaws for movement to clamping position.

14. A stop motion comprising bobbin lifting and clamping jaws, jaw operating means, and an independently movable bobbin lifting device carried by one of said jaws.

15. A stop motion provided with a pair of coöperating bobbin clamping jaws, jaw operating means, and a pivoted bobbin lifting finger carried by one of said jaws.

16. In a stop motion, in combination, bobbin clamping means, actuating devices therefor, and independently movable lifting means carried thereby.

17. A stop motion comprising a pair of co-operating bobbin clamping jaws, means for simultaneously moving said jaws in opposite directions, controlling mechanism therefor, and a vertically movable manually operated bobbin lifting finger carried by one of said jaws and movable independently thereof.

18. A stop motion comprising in combination, a supporting bracket, a pair of co-operating bobbin clamping jaws extending upwardly therefrom and pivoted thereto, a spring actuated slide coupled to said jaws to simultaneously move the same in opposite directions, trip mechanism for holding said slide and the jaws in set position, and a releasing device for said trip mechanism comprising a broken thread detector.

19. A stop motion comprising in combination, oppositely-movable coöperating bobbin lifting and clamping jaws, a spring device for actuating said jaws to clamp the bobbin against rotation, a trip mechanism for normally holding said means in set inoperative position against the tension of said spring, and releasing means for said trip mechanism comprising a movable thread receiving detector.

20. In combination, in a stop motion, a bracket comprising a box and an upwardly extending arm, bobbin gripping jaws fulcrumed to said arm, a spring actuated slide movable through said box and pivotally joined to said jaws to simultaneously swing the same in opposite directions, a trip mechanism in said box to normally hold said slide set against the tension of said spring, an electric motor in said box for releasing said trip mechanism, and a movable thread receiving detector arm carried by said bracket and controlling the motor actuating circuit.

21. In a stop motion, in combination, winding member stopping means, an electric switch controlled by the movement thereof and comprising an independently movable manually operative contact member, actuating mechanism for said means, a trip mechanism therefor, and a releasing device for said trip mechanism comprising an electric motor in circuit with said switch

and a thread receiving detector arm circuit closer in circuit with said motor.

22. A stop motion comprising winding member gripping jaws, means for simultaneously moving the same in opposite directions, and an electric switch comprising a stationary contact fixed with respect to said jaws, and a movable contact carried by and moving with one of said jaws.

23. A stop motion comprising oppositely movable pivoted winding-member clamping jaws, a manually operated member lifting finger carried by one of said jaws and manually movable independently thereof and provided with a switch contact movable therewith, and a stationary coöperating contact fixed with respect to said jaws.

24. In a stop motion, in combination, winding member stop means, a spring actuated slide for operating the same, a spring actuated, laterally swingable dog carried thereby, a swingable trip therefor for holding said slide in set position against the tension of its spring and comprising a laterally swingable arm provided with a shoulder for engaging said dog for holding the slide set, and means for releasing said arm to permit disengagement of its shoulder from said dog.

25. In a stop motion, in combination, winding member stop means, a slide for actuating the same, an actuating spring on the slide for moving the same in one direction, a laterally swingable dog pivoted to the slide and held in normal position longitudinally of the slide by said spring, a trip to engage said dog to hold the slide set against the tension of said spring and releasing means for the trip.

26. In a stop motion, in combination, a slide, stop means actuated thereby, guides for said slide, a spring acting on said slide to force the same on its operative stroke, a dog arranged longitudinally of said slide and fulcrumed thereto to swing laterally thereof, said spring acting on said dog to yieldingly hold the same in normal operative position with respect to said slide, said dog projecting laterally beyond the slide to engage a guide and limit the movement of the slide in one direction, a trip device arranged adjacent to said slide and having a shoulder to engage said dog and hold the slide set against the tension of the spring, and means for releasing said trip device to permit reciprocation of the slide.

27. In a stop motion, a box, an actuating slide movable therethrough, a dog pivoted thereto to swing laterally thereof and projecting laterally therefrom, a loose collar on said slide and resting on said dog, a slide-reciprocating coiled spring on said slide and bearing against said collar to yieldingly hold said dog in normal position, a laterally swingable arm in said box having a shoulder to

engage said dog and hold the slide set against the tension of its spring, a rockable trip lever to engage said arm and normally hold the same against rocking in a direction to release said dog, and means for actuating said trip lever to release said arm.

28. In a stop motion a pair of crossed pivoted levers at their free ends formed with opposing bobbin lifting and clamping jaws, 10 actuating means connected to said levers and constantly tending to swing the same to

bobbin gripping position, means normally holding said levers in inoperative or set position, and a trip mechanism for releasing said holding means. ¹⁵

In testimony whereof I affix my signature, in presence of two witnesses.
